UNITED STATES PATENT OFFICE.

HARRY A. ORLOPP, OF VENICE, CALIFORNIA, ASSIGNOR TO DAVID BAKER SMITH, OF LOS ANGELES, CALIFORNIA.

FORM TIE AND SPACER CONSTRUCTION.

Application filed November 6, 1923. Serial No. 673,060.

To all whom it may concern:

Be it known that I, HARRY A. ORLOPP, a citizen of the United States, residing at Venice, in the county of Los Angeles and State of California, have invented new and useful Improvements in Form Tie and Spacer Construction (#3), of which the following is a detailed specification.

This invention has to do with ties and spacers for concrete forms or the like; having to do with a tie and spacer device somewhat similar to those set out in issued Patent #1,468,790, dated September 25th, 1923, and in co-pending application Serial No. 651,813, filed July 16th, 1923, by the undersigned together with David Baker Smith. The devices which form the subject matter of this present application however, are somewhat different in structure from those shown in said patent and said prior application, in that in the prior structures the form board receiving notches are made, specifically, in V-shaped ridges, while in the present form the board receiving notches are made in flanges that extend up and down from the central flat plate. The specific formation of preferred forms embodying the present invention will be best understood from the following detailed description. The general object of the present invention is to provide a tie and spacer for concrete or like forms that will give strong and rigid support to the form boards or plates and at the same time is simple and inexpensive in its structure. It will be understood that where I refer to form boards I mean to include here form boards or plates or the like that are or may be used as the confining elements of a concrete or like form. It will likewise be understood that although I will describe my device as preferably being made of sheet metal, it is obviously not necessarily so made. These and other modifications and changes will be apparent to those skilled in the art from a consideration of the following detailed description of preferred and specific forms illustrative of the invention, which forms are shown in the accompanying drawings in which:—

Fig. 1 is a perspective of one form of my device;

Fig. 2 is an end view showing a modified formation of the form shown in Fig. 1;

Fig. 3 is an end view showing another modified formation of the form shown in Fig. 1;

Fig. 4 is a perspective illustrating another modified formation of the form shown in Fig. 1;

Fig. 5 is a small section illustrating the application of the device to a concrete form;

Fig. 6 is a perspective illustrating another form that my device may take;

Fig. 7 is a cross-section illustrating another method of forming the device of Fig. 6;

Fig. 8 is a fragmentary perspective showing a modification of the form of Fig. 6;

Fig. 9 is a perspective showing another modified form of the device;

Fig. 10 is a perspective showing another modified form of the device, and

Fig. 11 is an end view of the form of Fig. 10.

Referring first to Fig. 1 I show there a device that includes a central flat plate 10 with wide flanges 11 at each of its longitudinal edges. These flanges project equally above and below plate 10 and have form board receiving notches 12 formed in them above and below plate 10. Likewise, these flanges 11 may have reinforcing rod receiving notches 13 formed at their edges to take horizontal reinforcing rods; and plate 10 may have in its openings 9 to take vertical reinforcing rods. While I am describing these devices in the positions in which they appear in the drawings, it will be understood that the devices may be put in various positions. In Fig. 1 for instance, the device is shown in a position to act as a tie and spacer between opposite form boards of a form for a vertical wall, and in which the form boards are laid edge to edge on top of each other, as is illustrated in the vertical section of Fig. 5. However, it will be readily seen that the device will act just as well to tie and space between boards that are placed with vertical edges in abutment. Fig. 5 might as well be a horizontal section as a vertical section.

In using the device of Fig. 1 the lower notches 12 are placed over the upper edges of opposite form boards A and then the next course of form boards B is placed at the upper notches 12 the plate 10 thus lying between the adjacent and substantially abut-

ting edges of boards A and B. I have found in practice that relatively thin sheet metal in devices of this character will provide ample strength to resist all of the stresses to which the devices are subjected. Thus, in a great many cases it is not even necessary to slightly notch the edges of the form boards where plates 10 are placed, though this may be done if desired.

10 The flanges 11 not only provide members in which the notches 12 and 13 are cut but they also provide strengthening flanges for plate 10, strengthening it both as regards longitudinal tension and longitudinal compression.

15 In the form shown in Fig. 1, plate 10 may be secured to flanges 11 in any suitable manner, either mechanically, or by brazing or welding. In Fig. 2 I show how the whole 20 device may be made up of a single sheet of metal. Here the metal in the flanges is doubled at one side of plate 10, as is illustrated at 11^a. This not only provides an easy mode of manufacture but also further 25 strengthens the device.

20 In Fig. 3 I show what amounts to two channels secured together at their webs 10^a. These webs, forming the central plate, may be secured by riveting or by brazing or 30 welding. And in Fig. 4 I show how, in such a form as illustrated in Fig. 3, the ends of the flanges may be stiffened and reinforced against outward thrust, this being done by forming the metal diagonally as illustrated 35 at 14. This formation of the metal at 14 materially strengthens the outer and end parts 11^b of the flanges against bending or crumpling under the outward strains imposed upon those parts of the flanges by the 40 interior concrete pressure.

30 In Fig. 6 I show a structure similar to that shown in Fig. 1, excepting that, at one side of plate 10 there is only a single flange 11^c. This flange 11^c has the board receiving notches 12^c and reinforcing rod receiving notches 13^c; while the two flanges 11 at the opposite side of plate 10 are formed as in Fig. 1. In Fig. 7 I show a method of formation of the form shown in Fig. 6.

45 50 Here the lower flange 11^c is formed by bending the single sheet of metal back upon itself to make the lower flange double; and the two thicknesses of metal may be left unconnected, except at their lower edge or may be riveted or brazed or welded together.

55 In Fig. 8 I show the diagonal formation 14^c of parts of the metal adjacent the end portions 11^b of the flanges 11. This method of formation may be applied where the form 60 is specifically that shown in Fig. 6 or is specifically that shown in Fig. 7; with the result in either case of strengthening the outer end portions of the flanges 11.

65 In Fig. 9 I show a metal plate 10^d with a single flange 11^d in the center of each side.

Here the board receiving notches 12^d are cut down to the surfaces of plate 10^d. As a variation of the reinforcing rod receiving notches hereinbefore described, I show notches 13^d in bayonet slot form, for the purpose of more securely holding the reinforcing rods without the necessity of tying the rods into place. Such form of notches may be utilized in any of the forms of device herein described. 75

In Fig. 10 two oppositely extending flanges 11^e are shown at opposite edges of plate 10^e, the flanges having the board receiving notches 12^e and rod receiving notches 13^e. And I also show the metal formed 80 diagonally at 14^e to support the end portions of flanges 11^e as hereinbefore described.

Having described a preferred form of my invention, I claim:

1. A concrete tie and spacer embodying a 85 flat metal plate adapted to lie between abutting edges of form boards or the like and extending between opposite boards of the form, and flanges extending on opposite sides of the plate and at right angles thereto, said flanges having form board receiving notches.

2. A concrete tie and spacer embodying a 90 flat metal plate adapted to lie between abutting edges of form boards or the like and extending between opposite boards of the form, and flanges extending on opposite sides of the plate and at right angles thereto, said flanges having form board receiving notches and reinforcing rod receiving 100 openings.

3. A concrete tie and spacer embodying a 105 flat metal plate adapted to lie between abutting edges of form boards or the like and extending between opposite boards of the form, and flanges extending on opposite sides of the plate and at right angles thereto, said flanges having form board receiving notches, the notches being spaced back 110 from the ends of the flanges, and the metal being formed diagonally between the plate and the flange ends to strengthen the flange end portions against outward pressure.

4. A concrete tie and spacer embodying a 115 flat metal plate adapted to lie between abutting edges of form boards or the like and extending between opposite boards of the form, and flanges extending on opposite sides of the plate and at opposite edges thereof and at right angles thereto, said 120 flanges having form board receiving notches.

5. A concrete tie and spacer embodying a 125 flat metal plate adapted to lie between abutting edges of form boards or the like and extending between opposite boards of the form, and flanges extending on opposite sides of the plate and at opposite edges thereof and at right angles thereto, said 130 flanges having form board receiving

notches, the notches being spaced back from the ends of the flanges, and the metal being formed diagonally between the plate and the flange ends to strengthen the flange end portions against outward pressure.

6. A concrete tie and spacer embodying a flat metal plate adapted to lie between abutting edges of form boards or the like and extending between opposite boards of the 10 form, and flanges extending on opposite sides of the plate and at right angles thereto, said flanges having form board receiving notches, there being two such flanges extending from opposite edges at the same 15 side of the plate.

7. A concrete tie and spacer embodying a flat metal plate adapted to lie between abutting edges of form boards or the like and extending between opposite boards of the 20 form, and flanges extending on opposite sides of the plate and at right angles thereto, said flanges having form board receiving notches, there being two such flanges extending from both the opposite sides of the 25 plate.

8. A concrete tie and spacer embodying a flat metal plate adapted to lie between abutting edges of form boards or the like and extending between opposite boards of the 30 form and four flanges extending from said plate, two on each side thereof at its opposite longitudinal edges, the flanges extending substantially at right angles to the plate and having therein form board receiving notches near to but spaced from their ends, and the metal being formed 35 diagonally between the plate and the flanges to reinforce the end parts of the flanges against outward pressure of the form 40 boards.

9. A concrete tie and spacer embodying a metal plate adapted to lie between abutting edges of form boards or the like, and flanges extending from the opposite sides of the 45 plate, said flanges having form board receiving notches therein.

10. A form tie comprising a sheet metal body having longitudinal flanges bent in opposite directions each of the flanges having 50 alining notches cut therein for the reception of form boards the extensions of the

body beyond the notches being usable as bonds in building a brick veneer after the form boards are removed from the wall formed therebetween.

55

11. A combination form tie and spacer made of flat sheet metal formed with a long flat middle portion and two angle portions, one angle portion projecting in one direction from one side of said middle portion 60 and at substantial right angles thereto and the other angle portion projecting in the opposite direction from the other side of said middle portion and in a plane substantially parallel with the plane of said first 65 mentioned angle portion, the opposite ends of said angle portions having recesses struck out of them, the recesses at each end being opposite each other, one above and one below said middle portion for the purpose 70 indicated.

12. A combination form tie and spacer made of flat sheet metal formed with a long flat middle portion and two angle portions, one angle portion projecting in one direction from one side of said middle portion 75 and at substantially right angles thereto and the other angle portion projecting in the opposite direction from the other side of said middle portion and in a plane substantially parallel with the plane of said first 80 mentioned angle portion, said angle portions having notches cut therein to receive transversely placed bars and at their opposite ends having recesses struck out of them, the 85 recesses at each end being opposite each other, one above and one below the said middle portion.

13. A combination form tie and spacer of sheet metal and formed as a Z-bar in 90 cross section, the opposite outside portions having notches formed therein to receive reinforcing bars transversely thereof and at their opposite ends having notches therein 95 to receive form boards edgewise, one above the other, with the middle portion of said device therebetween.

In witness that I claim the foregoing I have hereunto subscribed my name this 1st day of November, 1923.

HARRY A. ORLOPP.
